Primary Examiner — Darlington Ly

(57) **CLAIM**

The ornamental design for a dashboard for electric bicycles, as shown and described.

DESCRIPTION

1. Dashboard for electric bicycles

1.1 is a top, rear, and right side perspective view of a dashboard for electric bicycles embodying my new design;
1.2 is a bottom, front, and right side perspective view thereof;

1.3 is a top plan view thereof;

1.4 is a bottom plan view thereof;

1.5 is a rear elevation view thereof;

1.6 is a front elevation view thereof;

1.7 is a left side elevation view thereof;

1.8 is a right side elevation view thereof;

1.9 is a top, rear, and right side perspective view thereof, wherein the display screen is in a state of use with environmental digital content being shown; and

1.10 is a top, rear, and right side perspective view thereof, wherein the display screen is in a state of use with environmental digital content being shown.

1 Claim, 10 Drawing Sheets
